UNITED STATES PATENT OFFICE.

CLARENCE A. PEIRCE, OF NEW HAVEN, CONNECTICUT, ASSIGNOR TO THE NEW ENGLAND PAPER BOX COMPANY, OF NEW HAVEN, CONNECTICUT, A CORPORATION OF CONNECTICUT.

DESIGN FOR A CANDY OR LIKE BOX.

Application filed April 14, 1926. Serial No. 17,288. Term of patent 14 years.

To all whom it may concern:

Be it known that I, CLARENCE A. PEIRCE, a citizen of the United States, residing in New Haven, New Haven County, Connecticut, have invented a new, original, and ornamental Design for a Candy or like Box, of which the following is a specification when taken in connection with the accompanying drawings, of which—

Fig. 1 is a front elevational view of a candy box embodying my new design.

Fig. 2 is a perspective view of the same showing the top of the box.

Fig. 3 is a rear elevational view of the box.

Fig. 4 is a sectional view on line 4—4 of Fig. 2.

I claim:

The ornamental design for a candy or like box substantially as shown.

CLARENCE A. PEIRCE.
